UNITED STATES PATENT OFFICE.

STEPHEN W. OLNEY, OF PLAINVILLE, MASSACHUSETTS.

MECHANISM FOR TWISTING WIRE.

SPECIFICATION forming part of Letters Patent No. 248,946, dated November 1, 1881.

Application filed August 13, 1881. (No model.)

To all whom it may concern:

Be it known that I, STEPHEN W. OLNEY, of Plainville, county of Norfolk, State of Massachusetts, have invented an Improvement in 5 Mechanism for Twisting Wire, of which the following description, in connection with the accompanying drawings, is a specification.

This invention has for its object the production of a simple, cheap, and efficient machine 10 to uniformly and closely twist together two or more pieces or lengths of wire used in the manufacture of jewelry, and for other purposes.

My invention consists, essentially, in a twisting-head to rotate the two or more lengths or 15 pieces of wire to be twisted together, and a spindle to revolve the wire-receiving spool, combined with a wire-feeding device located between the said head and spindle, the said feeding device acting also as a holder for the twist, 20 between it and the receiving-spool.

Figure 1 represents, in plan view, mechanism embodying my invention; Fig. 2, a side elevation thereof; and Fig. 3, a section on the dotted line x x , Fig. 2.

25 The frame-work A has below it hangers a' , to receive the shaft b , and above it uprights $a^2 a^3 a^4 a^5$, to receive the moving parts, to be described.

The driven shaft c in uprights a^2 has a pulley, c' , which receives upon it the belt to drive 30 the machine. This shaft c has upon it a cone-pulley, c^2 , having two effective diameters, which is connected with a cone-pulley, c^3 , also of two effective diameters, by an endless band, c^4 .

35 The cone-pulley c^3 is fast on the shaft d , mounted on the uprights a^3 , the speed of the shaft d being made variable by the said cone-pulleys in the usual manner, to rotate more or less rapidly the twisting-head d^2 , secured to the 40 said shaft d . The twisting-head carries the spool d^3 , upon which is wound the two or more lengths or pieces of wire, d^4 , to be twisted together by the rotation of the said head.

The spool d^3 in practice may be provided 45 with a suitable presser or brake, to prevent the spool rotating more rapidly than demanded for the proper delivery of the wire—such, for instance, as in the United States Patent to Elias Howe, Jr., September 10, 1846, or J. A. 50 Bradshaw, November 28, 1848.

The two or more lengths of wire to be twisted together are turned or wrapped once about the feeding cylinder or device e , having a flange or collar, e' , and placed on the shaft e^2 , which rotates in the bearing e^4 . The shaft e has a 55 grooved pulley, f , which, by a band, f' , over a large pulley, f^2 , on the shaft b , rotates that shaft. Shaft b has a grooved pulley, e^3 , which, by belt e^4 , extended over pulley e^5 , is made to rotate shaft e^2 and the feeding device e thereon, 60 the latter causing the wire to be fed forward as wanted by the receiving-spool g . The flange e' prevents the escape of the wire from the device e . The twist is put into the wire between the head d^2 and the feeding device e , more or 65 less twist being insured in accordance with the relative speeds of the head and feeding device, and the twist put into the wire passing beyond the feeding device by the rotation of the latter is kept uniform between the feeding 70 device and receiving-reel, and cannot run back to the head d^2 . Shaft e^2 has a pulley, g' , which is connected, by the crossed belt g^2 , with the pulley g^3 , and rotates the spindle n , which carries the receiving-reel g , upon which the twisted 75 wire is wound. To wind the twisted wire evenly and uniformly on the reel g , it is led between the fingers h of a guide-bar, h^2 , held in posts h^3 , and reciprocated parallel with the spindle n by an eccentric, h^4 , on an upright 80 shaft, h^5 , having at its lower end a pulley, h^6 , which receives a band, h^7 , extended over and driven by the pulley, h^8 , on the shaft b .

I claim—

In combination, the shaft c , its pulleys c^2 and f , the shaft d , its pulley c^3 , and head adapted to carry spool d^3 , the shaft b , its pulleys $e^3 f^2$, the shaft e^2 , its pulleys $e^5 g'$, and the cylinder e , the spindle n , to hold reel g and the pulley g^3 thereon, and the belts to connect the said 85 shafts and spindle, substantially as and for the purpose described.

In testimony whereof I have signed my name to this specification in the presence of two subscribing witnesses.

STEPHEN W. OLNEY.
